(57) **CLAIM**

The ornamental design for an alcohol detection device as shown and described.

DESCRIPTION

FIG. 1 is a perspective view illustrating the overall shape of the alcohol detection device, showing our new design; FIG. 2 is a front view depicting the front portion of the design;

FIG. 3 is a rear view illustrating the rear portion of the design;

FIG. 4 a left side view portraying the left side portion of the design;

FIG. 5 is a right side view depicting the right side portion of the design;

FIG. 6 is a top view illustrating the top portion of the design; and,

FIG. 7 is a bottom view showing the bottom portion of the design.
